(57) CLAIM

The ornamental design for the brush head, as shown and described.

DESCRIPTION

FIG. 1 is a front right perspective view of the brush head; FIG. 2 is a top view thereof;

FIG. 3 is a left side view thereof;

FIG. 4 is a front view thereof with the rear view being a reverse mirror image thereof; and,

FIG. 5 is a right side view thereof.

The broken lines in the drawings are for illustrative purposes only and form no part of the claimed design.
